JAMES A. G. SEYBOLD, OF KANSAS CITY, MISSOURI.

CARD GAME.

Application filed April 27, 1928. Serial No. 273,395.

My present invention has reference to a game designed to be played by a pack of cards of a particular design, which pack is divided into suits each containing fifteen cards and 5 a joker or master card, the cards constituting the suits being numbered consecutively and each bearing similar designs to represent the players and equipment of a base ball game, but the designs in each set being differently 10 colored and each card in the suits having a different playing value, while the odd master card or joker has a superior value to any of the cards in the suits and wherein, by the use of such pack of cards, any number of players 15 from two to eight, will be afforded a clean, interesting and educational amusement in which all of the plays in a base ball game are represented.

To the attainment of the foregoing reference is to be had to the drawings, which accompany and form part of this application.

In the drawings:

Figure 1 is a plan view of one of the suits of cards in spread condition. 25 Figures 2, 3 and 4 are similar views of the remaining suits, arranged one against the other, and

Figure 5 is a plan view of the master card. 30 As disclosed by the drawings, the game comprises a pack of cards divided into four suits or sets of fifteen cards, and numbered consecutively from 1 to 15, together with an independent card which is in the nature of a master card or joker, but which I shall refer 35 to as the "King base ball player."

For distinction the suits or sets of the cards are in the drawings indicated by the character 1, 2, 3 and 4 and the independent or King base ball card by the numeral 5. The 40 figures or characters on the cards constituting the sets 1 to 4 are similar, but are differently colored. The successive numbers 1 to 15, printed upon the opposite corners of the cards in all the sets indicate the playing value of 45 such sets. The figures or characters on the cards constituting the set 1 may for instance be of pink or yellow. Those on the suit or set 2 may be blue, those on the suit or set 3 are black and those on the suit or set 4 are orange. 50 The card numbered 1 in each of the sets has imprinted thereon the representation of a base ball bat 6. For the convenience of the

players of the game two bats, one adjacent each edge of the said card is inscribed thereon and also on this card, adjacent to the numerical figure thereof and outward of the bat 6 there is imprinted "One strike." The next card of each of the series, opposite the number 2 imprinted thereon, is inscribed with the words "Two strikes" and beneath these 60 words there are the representations of two bats 7. The next card of the suit or set, adjacent to its number has inscribed thereon "Three strikes" and below these words there are the representations of three bats 8 and to 65 one side of the bats there is imprinted the word "Out." Card number 4 has imprinted thereon the words "Right fielder" and the representation of the player occupying this position in a base ball game. Card number 70 5 has imprinted thereon the words "Left fielder" and representations of players of such position in a base ball game. The next card has imprinted thereon "Center fielder" and the representation of a player for that 75 position in a game. Card number 7 has imprinted thereon "Short stop" and a representation of a player of this position. Card number 8 has imprinted thereon "First baseman" and a representation of a player in such 80 position. Card number 9 has imprinted thereon "Second baseman" with the representation of a player. Card number 10 has imprinted thereon "Third baseman" and a pictorial representation of a player of such position. 85 Card 11 has imprinted thereon the word "Score" and a representation of a score board. Card number 12 has imprinted thereon "Base ball" and a representation of a playing ball. Card 13 has imprinted thereon the word 90 "Pitcher" and the representation of such player. Card 14 has imprinted thereon the word "Catcher" and a representation of a player of such position in a game, while card number 15 has inscribed thereon the word 95 "Umpire" and the representation of an umpire of a base ball game. The independent card or "King base ball" card 5 has inscribed thereon 12+, the words "King base ball," the representation of a sphere and such sphere is 100 divided by rightangular lines in quadrants, each of said quadrants being colored to represent the colors of the different suits or sets of the main playing cards.

Of course, the figures and representations occur only on the playing faces of the cards and the backs thereof may be suitably engraved, preferably with the figure of a base ball and suitable inscriptions with respect to the title of the game. The inscriptions on the faces of the different cards, it will be noted, represent the players and equipment for a base ball game and the purpose of such different figures on the different cards is to add to the excitement and thrills of the game as the same is being played. The object of the game is the winning of base balls and scores under certain or limited conditions and circumstances, within a certain or limited time.

The number, name, figure and color, on the face of the individual card determines the value and position when played in the game. The greater the card number the greater the value of the card in its particular color.

The player who gives out the cards from the pack to the players in the game is called the "dealer."

The game should be started by the player sitting at the head of the table, acting as dealer; or the dealer may be chosen or selected from some one of the players in some other way which is satisfactory to the crowd.

With the faces of the cards downward, the dealer thoroughly shuffles all of the cards in the pack; then taking the pack in hand with the faces of the cards downward, and beginning with the player at the left, the dealer deals out from the top of the pack, one card at a time consecutively to each player in the game; then repeats, until every player has the proper number of cards to play the game.

When the deal-out is completed and there are still cards left in the pack, the dealer distributes them face downward on the table to the left.

The total number of cards held in hand by a player is called a hand; and 7 cards in hand is the proper number with which to play the game.

The player at the dealer's left, should play the first card; then in like manner each player in their consecutive order to the left and ending with the dealer, should play one card: this is called a play. The player playing the card of highest value, takes all the cards played; this is called taking a "trick."

The first card played must be placed in the center of the table, face up. This card is called the "lead-out." The color of the lead-out card in the first play after the deal-out also determines the color of a trump; unless a trump color is determined in some other way.

The next player in consecutive order to the left, must now play a card in like manner as that of the first played, but the card played at this time, and the following card played by each of the following players should be of the color of the lead out card: this is called

"following suit." Suit or trump must first be played if the player holds such cards, but otherwise some other card may be played.

The suit color applies only throughout the playing for a trick; while the trump color remains the same during the play out of the entire hand. The suit and trump colors may be the same when a trump color is led out at the beginning of a trick play.

When a card is of the trump color its value is increased: The lowest trump card has a higher value than the highest suit card, and whenever trumps are played in a trick the highest trump card takes the trick.

Number 12+ (King base-ball) is higher in value, and will take number 12 (Base ball) in playing the game; but a Pitcher, Catcher, or Umpire, when trump; will take it when played in a trick.

King base ball card is always trump; and when the game is being played for the winning of Base balls it counts as 2 Base balls to the credit of the player who saves, or takes it when played in a trick.

Number 3 card (Three strikes-out) when taken in a trick, counts 1 against the player taking the trick; and is marked down on record as 1- (One in the hole) to the player taking the trick.

When a player takes, or saves a Base ball, or Score, in playing in a trick, 1 is marked down on record to that player's credit; but if a player takes an Out, in a trick, that player is marked down on record, 1-.

When both a Base ball or a Score, and an Out are taken in a trick, the Base ball or Score, balances the Out, and nothing is gained nor lost by taking the trick, so nothing is put on record.

When a player has 1 Base ball or a Score credited or record, and wins another in a following trick, this is added to that which is already on record; but if an Out is taken instead of a Base ball or a Score, then the Out is deducted from the Base ball or Score, which is on record, leaving the player with nothing on record.

The player who first wins a total of 9 Base balls or Score, wins the game.

Partners who first win a total of 15 Base balls or Scores, win the game.

The game may be played under the following rules or restrictions:

Rule 1.

The parties who wish to play in the game should be seated around about the different sides of the card table.

The game should be started by the player sitting at the head of the table, acting as dealer.

With the faces of the cards downward, the dealer thoroughly shuffles all of the cards in the pack: then taking the pack in hand with the faces of the cards downward, and begin-

120

125

130

ning with the player at the left, the dealer deals out from the top of the pack, one card at a time consecutively to each player in the game; then repeats until every player in the 5 game holds 7 cards in hand.

After the deal-out is completed, the cards remaining in the pack are discarded face downward upon the table at the dealer's left.

The player sitting at the left of the dealer 10 now takes a card from hand and places it face upward out into the center of the table. The color of this lead-out card is always the suit color, and in this case the trump color also; as it is the first card led out after a 15 deal-out. Each of the following players must first play a card of suit, or trump color, if they have it, before playing another color.

The trump color is now determined and 20 will remain of this same color for the entire playing of this hand.

When each player in the game has played out in consecutive order, one card upon the table; the player playing the highest card in value takes all of the cards played.

25 In playing the game, according to this rule, King base ball counts the same as 2 Base balls when taken in, or saved in the taking of a trick; and it is always trump, but a Pitcher, Catcher, or Umpire, when trump 30 will take it in a trick.

If any Base balls are taken in the trick the 35 player is credited with as many Base balls as are taken in, and if any Outs are taken in, the player goes in the hole the number of Outs taken in.

The player taking the trick, must now lead out the first card in the beginning of a new play. Any card of any color may be led out now, and the card led out will be the suit 40 color for this play. The trump color is the same as was used in the previous play.

A suit or trump card should now be played by each of the remaining players in their consecutive order to the left, and the trick should 45 be taken by the card of highest value, and the player taking the trick should be credited with any gains or loss derived from same.

The remaining cards in hand should be played out in like manner.

50 The player first winning a total of 9 Base balls wins the game.

Partners first winning a total of 15 Base balls wins the game.

Rule 2.

The dealer deals out the cards to the players and discards the remaining cards in the pack. The dealer then turns the top card of the discard pile face upward. The color 60 of this card is used as trump color for the playing of this hand: otherwise the game is played in like manner as that of Rule 1. When King base ball, a Base ball, or a Score is turned up in the discard for trump; 65 the same is credited toward game to the

dealer turning it—King base ball counting as 2, and Base ball, and Score counting as 1. When an Out is turned up it counts 1 against the dealer turning it.

70

Rule 3.

The dealer deals out the proper number of cards to the players and discards the remaining cards in the pack. The trump is determined by the bidding of the players. A 75 bid for trump, is a guarantee by the bidder of winning a certain number of Base balls during the play out of a hand, or a forfeiture of as many Base balls as bid. All 80 players look at their cards in hand to ascertain about how many Base balls they will be able to take and save in the play out of their hand. The player at the dealer's left makes the first bid: then each player in their successive order to the left makes a bid. The 85 highest bidder leads out the first card in the play and the color of this card will be the color of the trump during the playing of the hand. The game is continued in like manner as that of Rule 1.

90

When the hand is played out, and the highest bidder wins as many or more Base balls as bid; the number won is recorded to the credit of that player, but if the highest bidder does not win as many Base balls as 95 bid, the number bid is forfeited and counted as that many in the hole against that player.

Rule 4.

The game is played in like manner as that 100 of Rule 1 except that when out of suit, the player is not required to play a trump card in preference to some other card.

Rule 5.

The game is played in like manner as that 105 of Rule 2 except that when out of suit, the player is not required to play a trump card in preference to some other card.

Rule 6.

The game is played in like manner as that 110 of Rule 3 except that when out of suit, the player is not required to play a trump card in preference to some other card.

Rule 7.

The game is played in like manner as that 115 of Rule 1 except that a player is first required to play a suit color if such is held in hand, before playing any other color.

Rule 8.

The game is played in like manner as that 120 of Rule 2 except that a player is first required to play a suit color if such is held in hand, before playing any other color.

Rule 9.

The game is played in like manner as that 125

of Rule 3 except that a player is first required to play a suit color if such is held in hand, before playing any other color.

5 *Rule 10.*

The game is played in like manner as that of Rule 3 except that the highest bidder names the trump color, but is not required to lead out with the same in the first play of 10 the hand.

When playing the base ball game for the winning of Scores, the Base balls, and King base ball may be discarded from the pack. The playing is in accordance with the same 15 rules, and in like manner as that for the winning of Base balls.

Both, Base balls and Scores may be counted toward game in the same play, if desired.

The game may be played for points, by 20 counting King base ball as 2; and Score, Base ball, and Umpire, when trump as 1 point each. An Out, may also be counted as a point in the hole.

The base ball game may be played in many 25 different ways, but the rules laid down here should govern all the different ways in playing the game.

Having described the invention, I claim:
A base ball game to be played by cards,

divided into sets of fifteen each and a master card, the cards in each of the sets being consecutively numbered from 1 to 15, and and having a playing value according to the numbers, the first three cards in each of the sets having inscribed thereon respectively one, two and three base ball bats, the last mentioned number 3 card also having inscribed thereon the word "Out", the remaining cards of each set, except the cards numbered 11, 12 and 15, having inscribed 35 thereon the title or positions of players of a base ball game and representations of such players, the card of each set numbered 11 having inscribed thereon the word "Score" and a scoreboard, card bearing the number 40 12 having inscribed thereon the word "Base ball" and the representation of a base ball, card number 15 having inscribed thereon the word "Umpire" and the representation of such official, and the master card having 50 inscribed thereon the numeral 12+, the words "King base ball" and the representation of a sphere which is divided into quadrants each colored to correspond with the colors on the cards of the respective sets. 55

In testimony whereof I affix my signature.

JAMES A. G. SEYBOLD.
